US0D1011842S

(12) United States Design Patent (10) Patent No.: US D1,011,842 S
(45) Date of Patent:  Jan. 23, 2024

(54) CUP

(71) Applicant: YETI Coolers, LLC, Austin, TX (US)

(72) Inventors: Mark Carlson Rane, Austin, TX (US);
Matthew Brian Neeley, Austin, TX (US)

(73) Assignee: YETI Coolers, LLC, Austin, TX (US)

() Term: 15 Years

(21) Appl. No.: 29/755,722

(22) Filed: Oct. 22, 2020

Related U.S. Application Data

(63) Continuation of application No. 29/628,896, filed on Dec. 8, 2017, now Pat. No. Des. 899,862.
